UNITED STATES PATENT OFFICE.

WLADYSLAW NOGA, OF DETROIT, MICHIGAN.

SILK AND YARN THREAD TENSIONING AND WAXING DEVICE.

Application filed April 8, 1926. Serial No. 100,762.

The invention relates to improvements in devices for applying wax or the like to silk, 5 yarn and other kinds of thread used in connection with knitting machines or other fabric forming machines, and the present application is substantially the same as certain subject matter which was stricken from a parent application, Serial No. 721,921, filed June 23, 1924, by a requirement for 10 division.

All similar devices with which I am familiar, provide for waxing the thread or yarn at the time it is wound upon spools, which spools are used on the knitting machines. 15 My device however permits winding of the thread or yarn upon the spools in an unwaxed condition and provides for waxing the same when it is unwound from the spools upon the knitting machine, the benefits from 20 this being numerous. Less wax is necessary by the use of the invention, the knitting machine need not be stopped from time to time on account of the thread or yarn being wound upon the spools in a dry condition, 25 such condition preventing the yarn or thread from sticking upon the spools, which sticking now causes jerking of certain springs of the machine and results in automatic stopping of such machine, just as if the thread 30 or yarn had become broken.

The machine when provided with my device, will be kept clean of wax dirt, which is particularly advantageous in regard to the aforesaid springs, as when they become 35 gummed with wax or the like, they will not properly act to automatically stop the machine in case of breakage of the thread or yarn.

The machine, when equipped with my device, will produce a perfect material instead 40 of causing "drop stitch", because the thread that runs through my waxing device will be very elastic as freshly waxed and the hooks of the knitting machine needles can readily 45 catch it to properly knit the material. With present existing devices, the wax becomes dry on the thread or yarn, making it stiff and the result is that the hooks on the knitting machine needles will not catch it, 50 causing loop-holes in the material, commonly known as "drop stitch".

A machine when equipped with my invention, will produce more material during the same period of time and the material will 55 be of a superior quality, not only because it is free from loop-holes or the like, but be-

cause the threads will be of more uniform thickness. My invention provides for uniform waxing of the thread or yarn, whereas previously, the thread or the like was not 60 uniformly waxed, and wherever heavily waxed would cause a thickness in the completed material, and wherever lightly waxed, would cause a thin place.

One operator may attend to twice as 65 many machines when they are equipped with my invention and the work will be of better quality because said invention will eliminate frequent breaking of threads as they are drawn from the spools. These threads 70 retain their uniform strength and their freedom from each other, eliminating sticking of threads together.

Machines equipped with my invention need not be repeatedly adjusted and read- 75 justed with regard to hooks which support the work, which operations must follow each time the threads break. Very often, after each such operation, some hooks are left loose and when thus neglected, they will 80 break after awhile, causing more trouble, making the material non-uniform, losing time, etc.

It is one object of the invention to pro- 85 vide a new and improved waxing device from which all of the advantages hereinbefore enumerated will flow.

Another object of the present invention is to generally simplify the construction and so form a waxing device that it may be read- 90 ily assembled and disassembled and may be easily adjusted and repaired.

It is also an object to provide a novel 95 form of wax block-supporting table which rotates with the block under influence of linear movement of a thread being waxed, and to arrange beneath the thread and wax table, means of novel form to prevent lint, dust and the like from tangling about the post and bearing means by which the table 100 is rotatably supported.

Another aim is to provide clearance be- 105 tween the wax block and an upstanding sleeve on the table, which sleeve is received in an opening in the block, said clearance serving to collect any dirt, dye-stuff or the like from the thread and preventing it from covering the lower surface of the block, which would prevent proper waxing of the thread.

With the foregoing in view, the invention resides in the novel subject matter herein-

after described and claimed, the description being supplemented by the accompanying drawing.

Fig. 1 is a detail perspective view of the waxing device supported upon an adjustably mounted arm; and

Fig. 2 is a vertical central sectional view through the waxing device.

In the drawings above briefly described, the numeral 4 designates a beam supported in any desired manner. Upon one end of this beam, I have shown an angularly adjustable support 5 for a vertically swinging carrying arm 6 of the waxing device. By reason of the vertical swinging of this arm, desired tensioning of the thread being waxed, is effected. There may be any desired number of the supports 5, arms 6 and waxing devices and if desired, two or more of said supports 5 may be mounted upon each beam 4. Thus, either one or a battery of many of the tensioning devices may be arranged on one beam 4, while several beams 4 may be arranged on one machine.

The waxing device includes an upstanding spindle or post 7 having its lower end threaded and passed through an opening in the carrying arm 6, a nut 8 being threaded upon the lower end of said post or spindle in contact with the lower side of said arm. Arranged upon the upper side of the arm 6, in concentric relation with the post or spindle 7, is a cup 9 which is preferably of hemispherical form. The bottom of this cup is formed with a central opening 9' through which the post or spindle 7 passes, a nut 7' being threaded upon said post or spindle in contact with the bottom of the cup, so as to not only tightly secure said cup in place, but to rigidly anchor the post or spindle, and permit vertical adjustment of it.

Closing the open upper side of the cup 9 and forming a table to support a wax cake W, is a disc-like plate or cap 10 having a depending, flared skirt or flange 11, the latter being spaced outwardly from the annular exposed edge of the cup 9. By the provision of this cup, the table closing its open upper side, and the flange 11, no lint, threads, dirt or the like can reach the lower portion of the post or spindle 7 to interfere with proper action of the device, and the upper portion of said post or spindle is covered and thus protected, as will hereinafter appear.

The table 10 is formed with a central opening 12, larger than the post or spindle 7, and the lower end of a cylindrical tube or sleeve 13 is tightly pressed into said opening and is thus rigidly attached to the table 10. Pressed firmly into the lower end of tube or sleeve 13 and crowding it tightly outward against the wall of the opening 12, is a bushing 14 whose lower end is provided with an outstanding annular flange 15 lying tightly against the lower side of the table

10, serving still further to obtain a tight, rigid connection between said table and the sleeve 13.

Pressed tightly into the upper end of the tube or sleeve 13, is a bearing cap 16 having a suitable bearing seat 17 in its lower side to rest on ball 18, which ball is preferably integral with or secured to the upper end of the post 7. By this arrangement, the entire weight of the rotatable parts of the device and the wax cake W is supported anti-frictionally upon the upper end of the post or spindle 7, and the bushing 14 which surrounds said post or spindle, merely holds the table against angling with respect to the adjacent, stationary parts. When the table 10 is thus supported, there is from one to two-thousandths of an inch clearance between it and the cup 9, which clearance may be obtained by using the nuts 7' and 8 to vertically adjust the post or spindle 7 to the required extent.

The wax cake W, it will be observed, is of cylindrical form and is provided with an axial bore 19 to receive the sleeve or tube 13, and the lower portion of this wax cake is counterbored at 20, providing clearance between it and said tube or sleeve, so that any lint, dirt, dye-stuff or the like from the thread 21 may accumulate in this clearance space instead of coating the lower side of the wax cake and interfering with the proper waxing operation.

Guiding means for the thread may well comprise an inverted L-shaped eye member 22 having thread guiding eyes 23 and 24, spaced different distances from the vertical part or shank 25 of said member. This shank passes through or into an opening 26 in the arm 6 and is held by a set screw 27. When this screw is loosened, the entire member 22 may be raised or lowered as occasion may demand, to properly guide the thread 21 on a level with the table 10, and said member 22 may be swung laterally so as to guide the thread to the desired portion of the device. This adjustability is exceptionally desirable when a table of one size is removed and another table substituted to carry either a larger or a smaller cake of wax, as the case may be.

While the operation of the device would probably be understood from the foregoing, it may be briefly explained as follows:

The thread is drawn between the wax cake W and the supporting table 10 and by reason of the fact that the thread engages adjacent faces of the cake and the table at points spaced from the post or spindle 7 and the bearing sleeve, rotary motion will be imparted to the block and to the table. The waxing operation is facilitated by having the wax cake rotate and it will of course be understood that this cake is free to move downwardly upon the post or sleeve 13, as

it wears away. The weight of the wax resting upon the thread as well as the rotary movement of the wax cake and table, are instrumental in effecting the desired waxing 5 operation.

As excellent results are obtainable from the details disclosed, they are preferably followed. However, within the scope of the invention as claimed, variations may be 10 made.

I claim:

1. A thread waxer comprising, a substantially vertical post, a cup surrounding the post near its lower end, a sleeve rotatable 15 about the upper portion of the post and adapted for passage through an opening in a wax cake, a thread supporting cap closing the upper end of the cup, a bearing bushing arranged centrally of the cap and 20 surrounding the medial portion of the post, and an anti-friction bearing between the adjacent outer ends of the post and sleeve.
2. A thread waxer comprising, a substantially vertical post, a cup surrounding the post near its lower end, a thread supporting table closing the upper end of the cup and extending radially beyond the edge of the latter, a depending skirt at the periphery 25 of the table, a bushing centrally disposed in the table and surrounding the medial portion of said post, a bearing sleeve secured around a portion of said bushing and extending upwardly beyond said post for passage through an opening in a wax block, and a bearing 30 cap connecting the outer ends of the post and sleeve and closing the end of the latter.

3. A thread waxer comprising an upstanding post, a thread supporting table having an opening through which said post passes, the opening being considerably larger than 40 the post, a sleeve surrounding the post above said table and having a bearing resting on said post, the lower end of said sleeve being tightly pressed into said opening, and a bushing tightly pressed into the lower end 45 of the sleeve to crowd the latter outwardly against the wall of said opening, the lower end of said bushing being provided with outstanding means lying tightly against the lower side of the table, said bushing rotatably surrounding said post.

4. In a thread waxer, an upstanding post, a thread supporting table having an upstanding bearing sleeve around and protecting the upper portion of said post, and dirt excluding means adjacent to the lower end of the post, said means comprising an upwardly opening cup tightly secured to and surrounding the post with its upper edge in close proximity to the lower side of the 60 table, and a depending annular skirt on the edge of said table, surrounding said cup.

5. In a thread waxer, a rotatable table having an upstanding cylindrical member at its center, and a cake of wax bored vertically 65 to receive said member, the lower portion of said wax cake being counterbored to form a dirt receiving chamber thereby keeping the waxing face of the cake clean.

In testimony whereof I have hereunto 70 affixed my signature.

WLADYSLAW NOGA.
